UNITED STATES PATENT OFFICE.

FRITZ BLASER, OF AARAU, SWITZERLAND.

ALTERNATING-CURRENT RECTIFIER.

Application filed July 27, 1922. Serial No. 577,982.

To all whom it may concern:

Be it known that I, FRITZ BLASER, a citizen of the Republic of Switzerland, residing at Aarau, Canton of Aarau, Republic of Switzerland, have invented certain new and useful Improvements in and Relating to Alternating-Current Rectifiers, of which the following is a specification.

This invention relates to alternating current rectifiers and has for its main object to provide an apparatus by which an alternating current may be converted into a pulsating continuous current for charging accumulators or the like without sparking and without wasteful discharge of the accumulator during the period when the alternating current wave is near zero.

A further object of the invention is the provision of apparatus of this character in which the discharge current from the accumulators may be utilized to assist in carrying an overload of the alternating current circuit.

According to the present invention, a plurality of contact elements and an inductance are connected in series with an accumulator and form, at the moment the alternating current wave is at zero and the contact elements are changed over, a closed circuit through which the flow of discharged current from the accumulator is minimized and opposed by the choking effect of the inductance, the contact elements being electromagnetically actuated in response to the reversals of current in the alternating current circuit.

In the accompanying drawing wherein several approved embodiments of the invention are illustrated:—

Figure 1 is a diagrammatic view of one form of the rectifier, the contact elements being shown in their transitory positions.

Figs. 1^a and 1^b are detail views showing the alternative positions of the contact elements.

Figs. 2 and 3 are diagrammatic views of modifications of the rectifier.

Referring to the drawing in detail, and more particularly to Fig. 1, *a* is a polarized armature which is caused to vibrate by an electromagnet *f*, one end of the coil of which latter is connected with a conductor 10 forming part of an alternating current circuit 10—11 whereby the spring contact element *c* which supports the armature *a* is caused to vibrate in synchronism with the frequency of the alternating current. A

stationary contact element *b* engages on the same side as the oscillating contact element *c* against the double spring contact *d* and when at rest, the oscillating contact element *c* rests lightly against the double contact element *d*.

s' and *s²* are accumulators and *g* indicates a branch conductor of the conductor 11 which is connected with the negative pole of the accumulator *s'* and with the positive pole of the accumulator *s²*. The negative pole of the accumulator *s²* is connected by a conductor *i* with the stationary contact element *b*, a choke coil or other inductance *e* being interposed in said conductor. The positive pole of the battery *s'* is connected with the armature actuated contact element *c* by a conductor *h* while the other contact element *d* is connected with the alternating current conductor 10.

The two different positions of the contact elements are shown in Figs. 1^a and 1^b as they occur at the apex of the alternating current waves, Fig. 1^a illustrating the position for one wave and Fig. 1^b the position for the other wave. The different sets of arrows show the flow of current for the two positions of the contact elements, the full arrows showing the direction of current flow with the contact elements in the position illustrated in Fig. 1^a during the charging period of the accumulator *s'* and the dotted arrows indicating the direction of current flow with the contact elements in the position indicated in Fig. 1^b during the charging period of the accumulators *s²*.

The operation of the rectifier for charging the accumulators is as follows: The polarity of the armature *a* is such that an alternating current impulse flowing through the coil of the magnet *f* in the direction of the full line arrow will charge the core of the electromagnet in such sense as to attract the armature *a* thereby moving the double contact element *d* off of the stationary contact *b* and permitting the current to flow from the conductor 10 through the contact elements *d*, *c*, conductor *h*, accumulator *s'* and branch conductor *g* to the conductor 11. The next current impulse in the alternating circuit flows in the opposite direction as indicated by the dotted arrows and, reversing the polarity of the electro-magnet *f*, repels the armature *a*, moving the latter to the position indicated in Fig. 1^b and interrupting the flow of current through the accumulator *s'* and closing the electrical connection between the sta-

tionary contact element *b* and the double contact element *d*. With the double contact element in this position, the current flows through the conductor 11 in the direction of the dotted arrow and enters the positive side of the accumulator *s*² through the branch conductor *g* and thence into the conductor 10 through the conductor *i*, inductance *e* and contact elements *b* and *d*.

- 10 During the brief period when the two contact elements *b* and *c* both engage the double contact element *d* and while the alternating current wave is at zero, the accumulator *s*² is connected in series with the inductance *e* and the other accumulator *s*' through the conductor *i*, inductance *e*, contact elements *b*, *d* and *c*, conductor *h*, accumulator *s*' and branch conductor *g*. Due to the arrangement of the double spring contact element 15 *d* relative to the stationary contact element *b*, the time interval of actual contact between the two contact elements *b* and *c* and the double contact element *d* is, however, reduced to such a negligibly short period, 20 that the inductance *e* effectively acts to prevent the growth of the accumulator current to its full value and hence wasteful discharge of the batteries due to the short circuit is avoided while at the same time the 25 tendency of sparking at the contact points is reduced. Furthermore, the inductance *e* prevents the back flow of current from the accumulator *s*² into the alternating current circuit when the fluctuating impressed electromotive force of the rectified current is 30 less than the counter electro-motive force of that accumulator; the coil *f* performing a like function for the accumulator *s*'.
- When it is desired to discharge the current 35 of the accumulators *s*' and *s*² into the alternating current circuit 10-11, the conductors *h* and *i* of the positive and negative poles of the accumulators *s*' and *s*² respectively, may be interchanged, a double throw switch 40 of the type indicated at 30 being used for the purpose. The same effect may be also obtained by reversing the polarization of the armature *a*. The effect of either one of the above mentioned changes is to so connect 45 the accumulators with the alternating current circuit that their electromotive force is added to that of the alternating current circuit and the accumulators thus assist in carrying such excessive loads as may be imposed 50 on the alternating current circuit or in instances where the efficiency of the source of the alternating current falls below normal. With the rectifier apparatus operating in this manner, the accumulators are 55 caused to intermittently discharge into the alternating current circuit in synchronism with the frequency of the alternating current circuit and in proper phase relation to the alternating current.

60 In the modification of the invention illus-

trated in Fig. 2 there is shown an arrangement of two sets of contact elements, *b*, *c* and *d*, and *b*', *d*' and *c*' which are controlled according to the frequency and direction of current flow in the alternating current circuit 10-11 and operate to supply a unidirectional current to the accumulator *s*. In this arrangement, the conductor 10 is connected with the coil of the electromagnet *f* and with the double spring contact element 75 *d*' of the lower set of contact elements. The double spring contact element *d* of the upper set of contact elements is connected with the alternating current conductor 11 while the armature actuated contact element *c*' of the 80 upper set and the stationary contact element *b* of the lower set are both connected by a conductor *h*' with the negative pole of the accumulator *s*. The stationary contact element *b*' of the upper set and the armature actuated contact element *c* of the lower set are connected by conductors *g*' with the inductance *e* which latter is also connected with the positive pole of the accumulator *s* by a conductor *i*.

90 In this form of the invention two armatures *a* and *a*' are utilized to actuate the contact elements *c* and *c*', respectively, both armatures being polarized in a like sense and arranged adjacent the opposite poles of the 95 electromagnet *f*.

100 In operation, an alternating current impulse flowing in the direction of the full line arrow over the alternating current conductor 10 passes through the coil of the electromagnet *f* and energizes the latter in such sense as to cause the attraction of the armature *a*' and the repulsion of the armature *a* so that contact between the contact elements *b* and *d* is interrupted and the current flows 105 from the double contact element *d* through the contact element *c*, conductor *g*', inductance *e* and conductor *i*' to the positive pole of the accumulator *s*. From the negative pole of the accumulator *s* to the conductor 110 11 of the alternating current circuit, the current follows the path indicated at *h*', *c*' and *d*'. Upon reversal of the direction of the flow of current in the alternating circuit, the 115 polarity of the magnet *f* is reversed thereby attracting the armature *a* and repelling the armature *a*'. With this change in the positions of the armatures, the double contact elements *d* and *d*' engage their respective stationary contact elements *b* and *b*' and the alternating current impulse flowing in the direction of the dotted line arrow from the conductors 11 flows through the double contact element *d*', stationary contact element *b*', conductor *g*', inductance *e*, conductor *i*' to the positive pole of the accumulator *s* and from the negative pole of said 120 accumulator through the conductor *h*', stationary contact element *b*, and double contact element *d* to the coil of the electro- 125 130

magnet f and alternating current conductor 10. In this form of the invention, the inductance e acts in the same manner as described in connection with the form illustrated in Fig. 1, when the several contact elements pass through the transitory stages illustrated.

Referring to the modification of the invention illustrated in Fig. 3, two sets of contact elements b , c and d , and b' , c' and d' are also used, the double contact elements d , d' of the respective sets being connected with the negative and positive poles, respectively of the accumulator s through conductors 20 and 21. The armature actuated contact elements of the upper set and the stationary contact element b' of the lower set are connected in series with an inductance e^2 and with one terminal of the coil of the electro-magnet f , the opposite terminal of which latter is connected with the conductor 10 of the alternating current circuit. The stationary contact element b of the upper set and the armature actuated contact element c' of the lower set are both connected through branch conductors 22 with the conductor 11 of the alternating current circuit, an additional inductance e' being interposed between the contact elements b and c' . As in the form of the invention illustrated in Figure 2 the two armatures a and a' are polarized in the same sense and upon energization of the electromagnet f are simultaneously moved in the same direction, either upward or downwardly. Assuming an alternating current impulse to be flowing in the direction of the full line arrows over the conductor 11, the current passes through the conductor 22 to the armature actuated contact element c' , double contact d' and conductor 21 to the positive pole of the accumulator s . From the negative pole to the accumulator, the current flows from the conductor 20 through the double contact element d , armature actuated contact element c , inductance e^2 and coil of the electro-magnet f to the conductor 10. Upon reversal of the flow of current in the alternating current circuit, the current traveling in the direction of the dotted line arrow over the conductor 10 energizes the coil of the electromagnet f and causes upward movement of the armatures a and a' whereby the double contact elements are permitted to engage the stationary contact elements b and b' . Passing through the coil of the magnet f the current is conducted to the stationary contact element b' , double contact element d' and conductor 21 to the positive pole of accumulator s and from the negative pole of the latter through the conductor 20, double contact element d , stationary contact element b to the alternating current conductor 11 through the branch conductor 22 and the inductance e' . In this form of the invention

the inductance e^2 has the same choking effect on the current during the brief period when the battery circuit is closed, while by the provision of the additional inductance e' , the choking effect of the inductance e^2 is balanced or equalized so that both curves of the alternating current wave will have identically the same charging effect on the accumulator s . This figure further suggests the use of a coil 23 connected across the conductors 20 and 21 of the accumulator s for polarizing the armature a' in the desired sense.

What I claim is:—

1. In an apparatus of the character described, a source of direct electromotive force, a circuit including said source, contact elements connected in series in said circuit, an alternating current circuit connected with the first mentioned circuit, one of said contact elements being movable and two other of said contact elements being both arranged on and engageable with the same side of the movable contact element, one of the last mentioned two contact elements being movable and the other contact element being stationary and normally engaged by the first mentioned movable contact element, and electromagnetically actuated means associated with said contact elements and actuating the latter to change the connections between the alternating circuit and said source of current in accordance with the alternations in the flow of current through said alternating current circuit. 100

2. In an apparatus of the character described, a source of direct current, a circuit including said source, contact elements and an inductance connected in series in said circuit, an alternating current circuit connected with the first mentioned circuit, one of said contact elements being movable and two other of said contact elements being both arranged on and engageable with the same side of the movable contact element, one of the last mentioned two contact elements being movable and the other being stationary and normally engaged by the first mentioned movable contact element, and electromagnetically actuated means associated with said contact elements and actuating the latter to change the connections between the alternating current circuit and the source of direct current in accordance with the alternations in the flow of current through said alternating current circuit, said means acting to close the direct current circuit at the moment the connections are changed, and said inductance having a choking effect preventing rapid growth of the direct current in the closed direct current circuit. 120

3. In a current rectifier, a stationary contact element, a resiliently supported double contact element normally engaging the stationary contact element, and a vibratory 130

- armature actuated contact element, engageable with the double contact element on the same side of the latter as said stationary contact, the vibratory contact being adapted, 5 in one position, to disengage the double contact element from the stationary contact element, and, in its other position, to move out of contact with the double contact element and permit the latter to engage the 10 stationary contact element, said double contact element being adapted to simultaneously engage both the stationary and vibrating contact elements when the latter is in an intermediate position.
- 15 4. In an apparatus of the character described, an accumulator, a circuit including said accumulator, an inductance in said circuit, a plurality of sets of circuit changing contact elements interposed in said cir-

cuit, the contact elements of each set being 20 adapted, when in circuit changing position, to close the circuit including said accumulator and inductance, an alternating current circuit connected with certain of the contact elements of the respective sets, actuating armatures associated with certain other of said contact elements and electromagnet means interposed in the alternating current circuit and actuating said armatures whereby to change the contact elements in accordance with the 30 alternations in the flow of current through said alternating current circuit.

In testimony whereof I have affixed my signature in presence of two witnesses.

FRITZ BLASER.
